BOX FOR FLATWARE

Filed Aug. 5, 1948

UNITED STATES PATENT OFFICE
2,587,559
BOX FOR FLATWARE
Franklin C. Wetherbee, Middle Haddam, Conn.
Application August 5, 1948, Serial No. 42,561
4 Claims. (Cl. 206—45.13)

1 This invention relates to a box or container particularly designed for flatware such as knives, forks, spoons and the like.

In shipping or storing flatware such as knives, forks, spoons and so forth, it is usual to place one or two portions of the article beneath elastic straps in order to hold the articles in a position spaced from each other so that one will not cause scratching of another, and when an article such as a knife is placed beneath a loop to strap it to the bottom or lining of the box, it is rather difficult to remove the knife from position.

One of the objects of this invention is to provide an arrangement so that the article which is held in the box may be more easily removed from the box when it is desired to do so.

Another object of this invention is to cause the opening movement of the box to position the articles within the box in a different relative position from that in which they are located when the box is closed, so that the articles may be more readily removed from the box when the box is open.

More specifically, an object of this invention is to raise the lining of the box upon which the articles are mounted so that the same may be more accessible to the person removing the articles from the box.

With these and other objects in view, the invention consists of certain novel features of construction, as will be more fully described and particularly pointed out in the appended claims.

In the accompanying drawings:

Figure 1 is a perspective view of the box in closed position;

Figure 2 is a sectional view on line 2—2 of Figure 1;

Figure 3 is a perspective view of the box in open position and showing the lining raised so that the articles which are mounted thereon are readily accessible;

Figure 4 is a perspective view of a modified form of the box; and

Figure 5 is a sectional view of a fragmental portion of the box showing a modification.

In proceeding with this invention, a lining is loosely mounted in the box with respect to the inside surface of the body of the box, but secured along one of the flanges of the body which is distant from the hinge. Likewise, the lining is secured to the opposite member or cover of the box and there is secured in such a relation that when the box moves to open position, the lining being secured at points spaced from the hinge, tends to draw the lining out of the tray

and into a recessed portion of the box. As a result of this, the lining is caused to move into the recessed portion of the box and to be secured to the inner surface of the body of the box, so that when the box is closed, the lining is secured to the inner surface of the body of the box.

Figure 1 illustrates the box in closed position, the lining being secured to the inner surface of the body of the box.

Figure 2 illustrates the box in open position, the lining being secured to the inner surface of the body of the box.

Figure 3 illustrates the box in open position, the lining being secured to the inner surface of the body of the box.

Figure 4 illustrates a modified form of the box.

Figure 5 illustrates a fragmental portion of the box showing a modification.

2 or recess portion of the box and raise it to a point substantially the height of the flanges to the upper edge of which it is secured. Likewise, when the box is moved to closed position, the points to which the lining is secured move toward each other, thus slackening the lining and causing the lining to move into the recess in the box member so that the articles which are secured to the lining are moved into the tray or recess part of the container.

With reference to the drawings, 10 designates one member of the box and 11 another member of the box. These members are hinged together so that they may be swung toward or from each other.

In Figures 1 to 3 the member 10 may be considered the body of the box, while the member 11 may be considered as the cover. This member 10 has a flange 12 parallel to and distant from the hinge connection between the members and another flange 13 which is parallel to the flange 12 and adjacent the hinge connection. Other flanges 14 connect these two flanges 12 and 13 so as to provide an enclosure forming a recess 15 as shown more clearly in Figure 2.

In the showing in Figures 1 to 3 a similar arrangement is provided on the member 11 wherein there is a flange 16 and a second flange 17, which flanges are parallel to each other and to the hinge and located along opposite edges of the member 11, and connecting flanges 18 at right angles thereto serve to provide an additional recess for containing articles of silverware. A plate 19 is hinged as at 20 to the flange 17 and is hinged as at 21 to the lower part of the flange 13. This hinge plate serves to swing the flanges 17 and 13 into edge-to-edge abutting relation as shown in Figure 2.

The outer wall of the member 10 is illustrated as being composed of a plurality of plies of material and likewise the outer wall of the member 11 is similarly constructed. A covering 25 extends over both members and is connected by a loose portion 26 which extends across the hinge plate 19 which joins the two sections together.

In the showing in Figure 4 a somewhat simpler form is provided in that the member 30 is provided with flanges 31 and 32 joined by end flanges 33, while the other member of the box comprises a lid or cover 34 which has no flanges but is hinged as at 35 directly to the flange 32.

In Figure 5 the flanges 61 on one member 62, and 63 on the other member 64 are hinged directly together at 65.

A lining for the construction above described

in Figures 1 to 3 is designated generally 36 and extends from flange 12 to flange 16 (when the box is open as shown in Figure 3) unconnected to either of the members except at these extreme distant locations of the flanges. This lining 36 is divided into relatively stiff sections, one section 37 which is of a size to fit between the flanges 12 and 13 and their connecting flanges 14, there being another section 38 of a width substantially the height of the flange 12, this being hinged to the section 37 along the line 39 parallel to the hinge connection between the members. Similarly the other member 11 of the box has a section 40 of a size to extend from flange 16 to flange 17 and between the connecting flanges 18, while there is a section 41 secured to the flange 16 and hinged along the line 42 to the section 40. A section 43 connects the sections 37 and 40 and is hinged to the section 37 as at 44 and to the section 40 as at 45. This section 43 is of a width or depth substantially equal to the combined depths of the flanges 13 and 17 when in edge-to-edge relation. Thus, as shown in Figure 2, when the box is in closed position, the lining will snugly fit into the container.

In the showing in Figure 4 the section 47 is similar to the section 37 which has joined to it at one edge the section 48 hinged as at 49. However, the section 50 is secured along the inner surface of the member 34 over an area substantially equal to the section 47 and which has no flanges. A section 53 which is comparable to the section 43 in this case is of a width equal to the section 48, as there are no flanges on the cover or section 34 which must be compensated for.

In some cases where it is desired to hinge the flanges together as in Figure 5, I provide a support for the lining as at 66 in member 62, and 67 in member 64 so that the lining sections 68 and 69 will rest upon these supports when drawn to raised position.

The supports 66 and 67 also serve to cause the lining to fill the recess in the case when the case is closed, which otherwise might sag into the recess.

The lining, in each instance, has straps such as 55 and 56 spaced along it at locations where it is desired to mount articles of silverware such as shown in dotted lines at 57 in Figure 3.

It will be apparent that when the box is in closed position, the lining sections will lie as shown in Figure 2, whereas, when the members are moved to open position, such as shown in Figure 3, inasmuch as the distance between the flanges 12 and 16 becomes greater as the members 10 and 11 are moved apart, the lining will be stretched and pulled out of its recess between the flanges where it is lodged as shown in Figure 2 so as to be raised to the position which is the height of the flanges on both members permitting the articles of silverware or flatware to be easily withdrawn from beneath the loops which retain them in position. This same condition

occurs whether one or both of the members are flanged.

I claim:

1. A box for flatware comprising two members hinged together to move toward each other into closed position, at least one of said members having flanges to extend toward the other member when in closed position and provide a body having some containing depth, a first flange parallel to the hinge connection at the edge of the member opposite the hinge with other flanges at right angles thereto, a lining secured to the first flange at its free edge and loosely covering the flanged member between and free of said other flanges and extending across the hinge when the members are open and secured to the other member at a point spaced from said hinge connection said point being at least as high as the upper edge of the flanges when the other member is in open position and the lining is drawn tight in raised position whereby as the members are closed the secured points are moved closer together and the loose lining will move into the body of the box whereas as the members are swung open the secured points are moved apart and the lining is drawn taut and raised from between the flanges.

2. A box as in claim 1 wherein said lining has a section to substantially fit between the said flanges and cover the inner surface of said member and other sections of a dimension at right angles to the hinge line of the depth of the flanges, which sections are hinged to the first said section along lines parallel to the hinge line between said members.

3. A box as in claim 1 wherein both of said members have enclosing flanges and said flanges are hinged together and the point of securement of the lining is at the free edge of the corresponding flange on the other member.

4. A box as in claim 1 wherein both of said members have enclosing flanges and said flanges are hinged together, and the point of securement of the lining is at the free edge of the corresponding flange on the other member, and supports are provided in the members within the flanges and adjacent the hinge connection for said lining.

FRANKLIN C. WETHERBEE.
